UNITED STATES PATENT OFFICE

PHILLIP S. KIRBY, OF BARON, OKLAHOMA

EMBROIDERY NEEDLE

Application filed January 2, 1929. Serial No. 329,718.

This invention relates to embroidery needles and more particularly to a needle for use in the construction of rugs.

An important object of the invention is 5 the provision of an improved needle structure embodying an adjustable gauge for regulating the depth of the pile with which the rug is provided.

A further object of the invention is the 10 improvement of the needle structure shown in my prior Patent, No. 1,396,849, granted November 15, 1921, for Embroidery needles, to enable the same to be used in rug tufting.

15 A still further and more specific object of the invention is the provision of a structure having a gauge or stop for limiting movement of the needle through the material forming the base for the rug or other article 20 under construction and a novel and improved means for mounting and securing this gauge in adjusted positions.

These and other objects I attain by the construction shown in the accompanying drawing, wherein for the purpose of illustration 25 is shown a preferred embodiment of my invention and wherein:

Figure 1 is a side elevation of an embroidery needle constructed in accordance with 30 my invention;

Figure 2 is a plan view thereof;

Figure 3 is an enlarged longitudinal sectional view therethrough;

Figure 4 is a section on the line 4-4 of 35 Figure 3.

Referring now more particularly to the drawing, the embroidery needle comprises merging tubular and trough-shaped portions 10 and 11, the tubular portion being pointed 40 at its outer end and having an eye 12 formed therein. The tube has an opening 13 opposing this eye to facilitate the passage of the material employed in embroidering through the eye. The outer end of the base wall 14 45 of the trough-shaped section is likewise provided with an eye opening 15 for the passage of the embroidery material which extends through the trough-shaped and tubular sections to the eye 12. Each of the eyes 12 and 50 15 is preferably produced by punching the

material and leaving the short flap 16 attached at the inner edge of the opening and then flattening it down upon the inner end of the tubular or trough-shaped section, as the case may be, thus providing a rounded 55 inner edge for the opening, affording a smooth passage for the embroidery material thereover.

A gauge is provided comprising a U-shaped body portion 17 adapted to straddle the tubular section 10 and having at the ends of its arms parallel extensions 18 and 19 of different lengths and hereinafter referred to as the longer and shorter extensions respectively. The outer end of the 60 longer extension is provided with an inwardly directed terminal 20 adapted to interchangeably engage in any of a series of openings 21 formed in one side wall of the trough-shaped section. By the engagement of this 65 extension in a selected opening, the U-shaped gauge 17 may be arranged in predetermined 70 spaced relation to the eye of the needle, thus determining the extent to which the needle is projected through the material.

To preserve the alignment of the gauge proper, I secure upon the trough a guide 22 of the same cross-sectional characteristics as the trough and of such size that the trough may fit therein. The upper ends of the arms 80 23 of this guide are reverted in spaced relation to the arms and upon the inner faces thereof, so that they overlie and clamp upon the upper edges of the trough and hold the guide against displacement with relation 85 thereto. The inner faces of the arms of the guide in opposition to the outer faces of the arms of the trough are grooved, as indicated at 24, so that they combine with the walls 90 of the trough to produce guiding eyes slidably receiving the extensions 18 and 19. These guiding eyes are longitudinally elongated so that the extensions 18 and 19 and accordingly the gauge 17 may be very firmly held in position. The guide is secured to 95 the trough adjacent the junction of the trough with the tubular section, so that the end of the longer extension 19 is sufficiently exposed to permit flexing thereof, enabling the end portion 20 to be disengaged from an opening 100

21 in which it is disposed and shifted to another opening. This engagement serves to maintain the arm 19 in alignment with these openings so that there is little difficulty in making changes in the gauge position. The 5 guide, because of its position upon the trough, is so located that it reinforces the walls of the trough at the point where the needle is grasped by the hand in manipulation, thus eliminating the necessity for thickening the walls of the trough or reinforcing the same at this point to prevent destruction of the needle by the pressure applied thereto when forcing the needle through closely 10 woven fabrics.

15 The outer face of this guide is slightly roughened or milled, so that the grip of the fingers thereon may provide the necessary driving force of the needle without the necessity of the hand clamping the needle with such a grip that it rapidly becomes cramped.

20 It will be obvious that a structure of this character may be very readily and cheaply manufactured, may be very readily adjusted and manipulated and will be durable and efficient 25 in service. It will also be obvious that the construction hereinbefore set forth is capable of a certain range of change and modification without materially departing from the spirit 30 of the invention and I accordingly do not limit myself to such specific structure except as hereinafter claimed.

I claim:—

1. An embroidery needle comprising merging 35 trough-shaped and tubular sections provided adjacent opposite ends thereof with eyes for the passage of embroidery material, a guide exteriorly fitting and secured upon the walls of the trough-shaped section, a stop 40 associated with the tubular section and having an extension directed between adjacent faces of the guide and the wall of the trough and slidable in a groove formed in one thereof, said extension having a terminal portion 45 interchangeably engageable in a series of longitudinally spaced openings formed in said wall of the trough.

2. An embroidery needle comprising merging 50 trough-shaped and tubular sections provided adjacent opposite ends thereof with eyes for the passage of embroidery material, a guide exteriorly fitting and secured upon the walls of the trough-shaped section, a stop 55 associated with the tubular section and having an extension directed between adjacent faces of the guide and the wall of the trough and slidable in a groove formed in one thereof, said extension having a terminal portion 60 interchangeably engageable in a series of longitudinally spaced openings formed in said wall of the trough, the guide being exteriorly 65 roughened and being secured to the trough-shaped section adjacent its junction to the tubular section.

65 3. An embroidery needle comprising merg-

70 ing trough-shaped and tubular sections provided adjacent opposite ends thereof with eyes for the passage of embroidery material, a guide exteriorly fitting and secured upon the walls of the trough-shaped section, a stop 75 associated with the tubular section and having an extension directed along one side wall of the trough, said side wall having a series of longitudinally spaced openings, the extension having a terminal for selective engagement in said openings, the guide having a groove in the inner face of the wall thereof which opposes said wall of the trough through 80 which said extension is directed.

4. An embroidery needle comprising merging 85 trough-shaped and tubular sections provided adjacent opposite ends thereof with eyes for the passage of embroidery material, a guide exteriorly fitting and secured upon the walls of the trough-shaped section, a stop 90 associated with the tubular section and having an extension directed along one side wall of the trough, said side wall having a series of longitudinally spaced openings, the extension having a terminal for selective engagement 95 in said openings, the guide having a groove in the inner face of the wall thereof which opposes said wall of the trough through 100 which said extension is directed, the stop having a second extension directed along the opposite wall of the trough, the coacting wall of the guide having a groove for the reception of said second extension.

5. An embroidery needle comprising merging 105 trough-shaped and tubular sections provided adjacent opposite ends thereof with eyes for the passage of embroidery material, a guide exteriorly fitting and secured upon the walls of the trough-shaped section, a stop 110 associated with the tubular section and having an extension directed along one side wall of the trough, said side wall having a series of longitudinally spaced openings, the extension having a terminal for selective engagement 115 in said openings, the guide having a groove in the inner face of the wall thereof which opposes said wall of the trough through 120 which said extension is directed, the stop having a second extension directed along the opposite wall of the trough, the coacting wall of the guide having a groove for the reception of said second extension, said stop being U-shaped in form and straddling the tubular section, said extensions comprising angular continuations of the arms of the 125 stop.

In testimony whereof I hereunto affix my signature.

PHILLIP S. KIRBY.
